CLAIM

The ornamental design for a valve for mixing fluids, as shown and described.

DESCRIPTION

FIG. 1 is a perspective view taken from the top, front, and right side of the valve for mixing fluids of the present new design.

FIG. 2 is a front elevation view of the valve for mixing fluids of FIG. 1

FIG. 3 is a rear elevation view of the valve for mixing fluids of FIG. 1.

FIG. 4 is a left side elevation view of the valve for mixing fluids of FIG. 1.

FIG. 5 is a right side elevation view of the valve for mixing fluids of FIG. 1

FIG. 6 is a top plan view of the valve for mixing fluids of FIG. 1; and,

FIG. 7 is a bottom plan view of the valve for mixing fluids of FIG. 1.

The elements drawn in broken lines are aspects of the valve for mixing fluids which form no part of the claimed design.
